ABSTRACT

Game apparatus adapted to be played outdoors or indoors and including a shaft rotatably mounted at one end in a bearing of a base member either resting upon a horizontal playing surface or suspended from a ceiling. A target loop is provided on the other end of the shaft and one end of a flexible tether is looped or otherwise loosely connected to said shaft while a ball-like projectile is connected to the other end of the tether for projection to and through said target loops such as by kicking, pitching or otherwise.

PROJECTILE TETHERED TO ROTATABLE TARGET HOOP

CROSS-REFERENCE TO RELATED APPLICATION

This application pertains to an athletic type of game apparatus but in a limited way embodies principles similar to some in applicant's two additional co-pending application filed on even date herewith which respectively pertain to a table top type game, entitled Game Apparatus, and a bowling type game entitled Game Device.

BACKGROUND OF THE INVENTION

This invention pertains to a game apparatus which may be played either indoors or outdoors and is of an athletic nature as distinguished from a table-type game. Essentially, it embodies a target loop through which a projectile, such as a ball, is adapted to be projected in any one of number of different ways. The ball is connected to a shaft which supports the target loop by means of a flexible tether of predetermined length.

Many types of games have been developed heretofore which embody the basic principles of throwing, kicking, or otherwise moving a projectile or game piece through a target ring or loop. To a certain extent, applicant's prior Pat. No. 3,589,726, dated June 29, 1971, is illustrative of one form of game of the type to which reference is made. Other types of game apparatuses are possible of development, however, in which different objectives are embodied from those devices which have been developed heretofore.

SUMMARY OF THE INVENTION

It is the principal object of the present invention to provide game apparatus which essentially embodies a base adapted to be fixed stationarily to supporting means having a bearing in which one end of a shaft is rotatably supported, while the opposite end of the shaft has a target loop thereon and a ball-like projectile is connected by means of a flexible tether of predetermined length to said shaft, whereby the ball may be projected by any agreed-upon game rules, such as kicking, hitting, batting, pitching or otherwise, and the movement of the projectile, when projected with adequate force, results in the target loop being swivelly moved about the axis of its supporting shaft and thereby rendering certain situations of play possible which have not been available in ball and target loop-type games developed heretofore.

It is a further object of the invention, to provide, selectively, a plurality of different types of bases which may either be supported by gravity, due to the weight of the base, upon a horizontal playing surface without being fixed thereto, or another embodiment of the base has a pointed end which is adapted to be projected into the soil of an outdoor playing field or lawn, while still another type of base is adapted to be connected to an overhead surface, such as a ceiling, whereby the target loop depends downwardly from the supporting shaft.

A further object of the invention is to form the target loop from rod-like material from which the supporting shaft is formed and bend the end portion of said rod-like material, which is opposite the rotatably supported end thereof into said loop, but the tip of said bent end portion is spaced a limited distance from the part of the rod-like material which forms the opposite end of said

loop which is connected to said shaft, whereby the end of the tether which is connected to the shaft by a small ring or loop may be moved through said space and slidably move along the loop and shaft, said arrangement also permitting detachment of the connecting ring from the target loop when desired, such as for purposes of untangling the flexible tether from the shaft, as required.

Details of the foregoing objects and of the invention, 10 as well as other objects thereof, are set forth in the following specification and illustrated in the accompanying drawing comprising a part thereof.

BRIEF DESCRIPTION OF THE DRAWING

15 FIG. 1 is a partially sectioned and vertically foreshortened elevation of one embodiment of game apparatus which incorporates the principles of the present invention.

20 FIG. 2 is a fragmentary vertical elevation, partly in section, illustrating another embodiment of supporting base for the rotatable shaft which may be substituted for the base embodiment shown in FIG. 1.

25 FIG. 3 is a vertically sectioned view of a still further embodiment of base of the type adapted to be connected to an overhead surface, such as a ceiling, and may be used in lieu of the bases of the embodiments shown in FIGS. 1 and 2.

30 FIG. 4 is a vertical elevation in smaller scale than that employed in FIG. 3 but illustrating a substantially complete type of game apparatus intended to employ the embodiment of base shown in FIG. 3, the tether of said apparatus in FIG. 4 being foreshortened to accommodate the view to the sheet.

DETAILED DESCRIPTION

One embodiment of the present invention is shown in FIG. 1 in which a base 10 is provided with a lower peripheral flange 12 which is adapted to engage, by gravity, a horizontal supporting surface 14 such as a gymnasium floor, an outdoor playing field, a paved surface, or otherwise. If desired, the base 10 may be fixedly connected to the supporting surface 14 but, under circumstances where the base 10 is formed from a heavy metal casting, for example, the diameter of the flange 12 may be made adequate to support the base 10 solely by gravity in a manner to resist any appreciable tilting of the base with respect to surface 14 during play.

50 The base 10 is provided in its upper portion with a bearing sleeve 16 in which, for example, anti-friction bearing means such as a pair of ball bearing units 18 are mounted. The bearing units 18 preferably are spaced apart vertically a limited distance to afford rotatable support for the lower end of a substantially vertical shaft 20 which may be of any desirable length, from a few inches, to a number of feet such as possibly 6 or 8.

60 The shaft 20 preferably is made from metallic rod material and the upper end thereof is formed into a target loop 22 which, preferably, is of circular configuration of a predetermined diameter, such as of the order of several feet. Said dimension is stated for purposes of example rather than restriction, it being understood that, preferably, the diameter of the target loop 22 should be substantially larger than the diameter of the ball-like projectile 24 which is adapted to be projected through the loop incident to playing any of a number

of variety of games in which the apparatus is capable of being used.

From FIG. 1, it will be seen that the terminal end 26 of the rod-like material from which the shaft and target loop are formed is spaced from the bent portion 28 of the shaft and target loop to provide a preferably narrow space 30 which is for purposes to be described.

The projectile 24, as referred to above, preferably is of substantially less diameter than that of the target loop 22 and, for practical purposes, it has been found that the diameter of the projectile 24 should be no greater than one-half the diameter of target loop 22. The projectile 24 is connected to the target portion of the apparatus by means of a flexible tether 32 of any suitable material such as rope or twine of suitable composition and diameter, or rope made from synthetic resin fibers, such as Nylon rope, which is used for many types of marine purposes and is highly suitable to effect such connection of the projectile 24 to the target loop 22. If desired, a light-weight chain may also be employed for such purpose as well as metallic cable of small diameter.

One end of the tether 32 is fixedly connected to the projectile 24 in any suitable manner. The opposite end of the tether 32 preferably is tied to a small ring 34 which is of slightly larger diameter than that of the rod-like material from which the shaft 20 is formed. The thickness of the ring 34 also is at least slightly less than that of the space 30 of the target loop 22 in order that the ring 34 may readily be placed upon the shaft such as by inserting the ring 34 through the space 30 and then moving it around loop 22 and down shaft 20.

By way of exemplary description of how games may be played with the apparatus described above, assume that the projectile 24 is 6 or 7 inches in diameter, the shaft 20 is about 3 feet high, and the target loop 22 is about 18 or 20 inches in diameter. Under such circumstances, the tether 32 may be 12 or 15 feet long. Game play is initiated by one player kicking or hand-throwing the projectile 24 through the target loop 22 from the position where the projectile 24 lies upon the supporting surface 14 for example. If the projectile passes through the loop, the player scores a goal and, depending upon the rules of play may continue to kick and score until a miss occurs. The next player then takes their turn at play.

Depending upon the position of the loop 22 with respect to the player, this can be a difficult achievement, especially if the plane of the target loop 22 is not directly transverse to the line of sight of the player. In any event, if the projectile 24 is projected with considerable force through the target loop 22, it is readily conceivable that such projection can hit the side of loop 22 in a way that will spin the target loop 22 about the axis of shaft 20 for either a partial revolution or a number of revolutions, depending upon the force applied and the position of loop 22 when it is hit. Under such circumstances, if the tether 32 should become wound around the shaft 20 when it is desired to free the tether 32 from such situation, the ring 34 may be slipped through the space 30 and thereby facilitate the unsnarling or untangling of the tether 32 relative to shaft 20 and target loop 22. In normal play, if the projectile passes through target loop 22, the tether 32 usually will drop through space 30 in coming to a normal rest position.

The foregoing example is merely illustrative and it will be seen that, if desired, shaft 22 may be 6 or 7 feet,

or possibly even more in height. Various types of kicking or handbatting or pitching the projectile 24 through the target loop 22 may be resorted to in accordance with the agreed-upon rules of play. It also should be obvious that the apparatus may be used in play, either by a single player, or a plurality of players in competition with each other, and thereby afford amusement and recreation for those participating in it.

Referring to FIG. 2, it will be seen that an alternative type of base 36 is provided which is of a type that may be inserted into soil 38 of an outdoor playing field for example. Thus, the upper end portion 40 of base 36 preferably is cylindrical, while the lower end portion 42 is tapered preferably to a substantially sharp point to facilitate the positioning of the base 36 in the soil 38. The upper cylindrical portion 40 of base 36 includes an outer race or shell 44 of a needle bearing or roller bearing unit which includes needles or rollers 46 of predetermined length which surround an inner sleeve 48 of the bearing unit. The lower end 50 of the supporting shaft 20' is inserted through the inner sleeve 48 for rotatable support thereby and a set collar 52 is fixed to said shaft to determine the extent of reception of the lower end 50 thereof within the anti-friction bearing unit.

The length of the anti-friction bearing unit shown in FIG. 2 is adequate to enable the shaft 20' to resist reasonable bending stresses which may be imposed upon the shaft incident to playing games with the apparatus. It will be understood that for purposes of simplifying FIG. 2, a target loop has been omitted therefrom but it is to be assumed that the shaft 20' supports a target loop similar to loop 22 in FIG. 1. Correspondingly, the length of the shaft 20' also may be of any desired dimension such as from a few inches to a number of feet, as described above with respect to shaft 20 of the embodiment shown in FIG. 1. Said target loop also has a tether 32 and a projectile 24 connected thereto and the description of possible play set forth above with respect to the embodiment of FIG. 1 applies equally to that of the embodiment of base structure shown in FIG. 2.

Referring to FIGS. 3 and 4, still another embodiment of base structure is illustrated. In these figures, the base 54 may be cup-shaped, as shown in FIG. 3, and a roller or needle bearing unit 56 is closely fitted within the inner walls of the cup-shaped base 54, the bearing unit 56 being similar to that illustrated in FIG. 2, whereby repetition of the detailed description is omitted except to additionally state that the bearing unit 56 bottoms upon a lower annular flange 58 formed on the lower end of the shell of cup-shaped base 54. The upper end of said shell also is provided with a preferably annular flange 60 which extends laterally and is adapted to be fixedly connected to a horizontal overhead supporting surface 60, such as a ceiling, a horizontal overhead beam, or other suitable overhead supporting surface in a building structure.

From the foregoing description, it will be seen that the base 54 is intended to support a shaft 20" in depending manner. To accomplish this, the upper end of the shaft 20" extends through the inner sleeve or race of the bearing unit 56 and a nut 62 is threaded on the upper end thereof to prevent downward movement of the shaft relative to the base 54. The nut 62 operates in opposition to a set collar 64 which abuts the lower end of the inner sleeve of the bearing unit 56.

Referring to FIG. 4, which is a vertical elevation of an exemplary installation which employs the base 54 otherwise shown in FIG. 3, it will be seen that the lower end of the shaft 20" terminates in a target loop 22' to which a tether 32' is slidably and loosely connected at one end, by means of a small ring 34', while the opposite end of the tether 32' is connected to a ball-like projectile 24'. Under such circumstances, it is preferred that the length of the tether 32' be adequate to permit the projectile 24' to rest upon the playing surface 14' when the projectile is not in play.

By such foregoing arrangement, the projectile 24' will always be in position to be engaged, at rest, by a player, either by pitching, kicking, or hand-batting the projectile toward and/or through the target loop 22' in accordance with the method of play being followed by the players. As in regard to the preceding embodiments, the target loop 22' also is provided with a small space 30' through which the small ring 34' may be passed to either connect or disconnect the tether 32' to or from the target loop 22'.

From the foregoing, it will be seen that the present invention provides an athletic type of game utilizing a projectile arranged to be projected through a target loop but at all times restrained from movement away from the target loop beyond a maximum distance which is controlled by a flexible tether that is connected at its opposite ends respectively to the target loop and projectile. Various types of supporting base means are provided so as to enable the basic principles of the apparatus to be utilized and games played therewith upon various types of supporting surfaces, including even overhead surfaces, and regardless of whether the surfaces are of an indoor or outdoor nature.

While the invention has been described and illustrated in its several preferred embodiment, it should be understood that the invention is not to be limited to the precise details herein illustrated and described since the same may be carried out in other ways falling within the scope of the invention as illustrated and described.

I claim:

1. Game apparatus comprising in combination, a base adapted to be affixed stationarily to supporting means and having a bearing sleeve extending perpendicularly thereto and having anti-friction bearing means mounted therein, a shaft supported at one end within said anti-friction bearing means for free rotation relative to said base, a target loop formed at the opposite end of said shaft and comprising a circular continuation of said shaft, said loop being within a substantially vertical plane and the terminal end of said loop being spaced from the adjacent portion of said shaft to form a narrow space, a ball-like projectile having a diameter smaller than said target loop, and a flexible tether of predetermined length connected at one end to a ring loosely slideable upon said shaft and loop and capable of passing through said narrow space between said loop and shaft, and the other end of said tether being connected to said projectile, whereby said projectile may be projected by a player to and through said loop for scoring purposes with substantially no possibility of said tether being tangled upon said shaft or loop.

2. The game apparatus according to claim 1 in which said anti-friction bearing means is a needle bearing comprising concentric inner and outer sleeves between which needle bearing members are positioned for rotation, the inner sleeve of said needle bearing receiving said one end of said shaft to support the same rotatably relative to said base, a set collar mounted upon said shaft in a position spaced from said one end and arranged to abut the outer end of the inner sleeve of said needle bearing to limit the insertion of said one end of said shaft into said inner sleeve, and said base being cylindrical at one end to receive the outer sleeve of said needle bearing, and the opposite end being tapered to a point to permit the same to be inserted into the soil of an outdoor playing surface to support said apparatus for playing.
